US0D1047204S

(12) **United States Design Patent** (10) **Patent No.:** **US D1,047,204 S**
Cun (45) **Date of Patent:** **** Oct. 15, 2024**

(54) **MASSAGING DEVICE**

(71) Applicant: **Shenzhen Envision Technology Innovation Co., Ltd.**, Shenzhen (CN)

(72) Inventor: **Lang Cun**, Shenzhen (CN)

(73) Assignee: **Shenzhen Envision Technology Innovation Co., Ltd.**, Shenzhen (CN)

(**) Term: **15 Years**

(21) Appl. No.: **29/894,993**

(22) Filed: **Jun. 15, 2023**

(30) **Foreign Application Priority Data**

Jan. 10, 2023 (CN) 202330015869.3

(51) **LOC (14) Cl.** **24-01**

(52) **U.S. Cl.**

USPC **D24/215**

(58) **Field of Classification Search**

USPC D24/215, 200, 211, 212, 213, 214, 133, D24/107, 231

(57) **CLAIM**

The ornamental design for a massaging device as shown and described.

DESCRIPTION

FIG. 1 is a perspective view of a massaging device of the present invention.

FIG. 2 is a front view thereof.

FIG. 3 is a rear view thereof.

FIG. 4 is a right view thereof.

FIG. 5 is a left view thereof.

FIG. 6 is a top view thereof; and,

FIG. 7 is a bottom view thereof.

The broken lines represent portions of the massaging device that form no part of the claimed design.

1 Claim, 7 Drawing Sheets
